ADJUSTABLE BLADED IMPELLER

André Cornillon, Lyon, France

Application August 13, 1948, Serial No. 44,030
In France September 13, 1947

4 Claims. (Cl. 170—154)

1

My invention relates to multi-bladed rotors for the propulsion of craft and more particularly of aircraft.

One object of my invention is to provide a multi-bladed rotor of improved construction which will be more convenient in use than the known arrangements.

Another object of my invention is a rotor wherein full engine power will be used with high efficiency.

Still a further object of my invention is to provide a multi-bladed rotor which may give rise to such a lifting action that the aircraft equipped therewith will be transformed into a helicopter.

With these and other objects in view my improved multi-bladed rotor is preferably constructed as illustrated in the accompanying drawings in which:

Fig. 1 is a rear view of my improved rotor with parts in section, taken along line I—I of Fig. 3.

Fig. 2 is a fragmental plan view with section taken along line II—II of Fig. 1.

Fig. 3 is a plan view taken along line III—III of Fig. 1, the tiltable plate being supposedly removed.

Fig. 4 is an enlarged partial vertical section of the casing taken along the axis of a blade to show the mounting of the inner end of a rotor blade.

Fig. 5 is the corresponding plan view with the upper half of the casing supposedly removed.

Figs. 6, 7, 8 and 9 are enlarged detailed sections taken along lines VI—VI, VII—VII, VIII—VIII and IX—IX of Fig. 3.

Fig. 10 is a perspective view of the rotor supporting member.

Fig. 11 is an enlarged section showing a blade controlling roller in its guide.

Fig. 12 is a fragmental side view corresponding to Fig. 2 to show the pivotal attachment of the oscillatable plate to the supporting sleeve.

Fig. 13 illustrates the upper end of the rotor shaft, the driving pinion supposedly removed.

Figs. 14 and 15 are perspective views illustrating securing members for the circular roller guide.

Fig. 16 is a perspective sketch illustrating the operation of the gearing adapted to transform the relatively small angular oscillation of the controlling rollers into a large oscillation of the blades, the various members being supposedly spaced apart from each other for a better understanding of the drawing.

2

Fig. 17 is a side view of the guide-way for the controlling rollers, the position in full lines corresponding to the normal forward flight, the position in dash lines corresponding to hovering and the position in dotted lines concerning backward flight.

Figs. 18 to 20 are diagrams showing in full lines the slopes of the guide way and in dash lines the resulting variation of the blade pitch 10 at the three positions above-mentioned, it being understood that the slopes of the guide-way have been greatly exaggerated for the sake of clearness.

Fig. 21 is a perspective view of an aircraft provided with three rotors according to my invention.

My improved rotor comprises a four-armed casing formed of upper and lower parts 1, 2 (see Figs. 1, 4 and 5) enclosing four radially 20 disposed shafts 3.

Each shaft 3 has an enlarged portion and is carried by two ball bearings, as indicated at 4 and 5, while two other ball bearings 6 and 7 are provided to prevent axial displacements and to 25 afford smooth rotation. Oiling is ensured by an axial canal 8 with branch passages 9, a free space being left between shafts 3 and the inner faces of the casing.

Shafts 3 form the tail portions of the blades 30 10 (Fig. 1). The latter are spoon-shaped members made of forged and stamped aluminum alloy. They rotate together with casing 1, 2 about the vertical axis thereof, as explained below, and they are at the same time rotatable about their 35 own axis.

Casing 1, 2 is also made of light alloy. Its vertical end faces are provided with steel sheets 11 (Fig. 4) fixed by screws 12 (Fig. 6) and united with each other by screwed steel tongues 13, 14. 40 One of the latter has a raised end carrying a coil spring 15 and at 90° thereof there is also provided another angle member 16 carrying another coil spring 17 turned towards spring 15. Between springs 15 and 17 there is arranged a flat 45 radial member 18 formed of the ends of a steel band wholly or partly surrounding the corresponding shaft or tail portion 3 and secured thereto by screws. In this manner when the 50 blades oscillate through 90° as hereinafter explained, member 18 alternately depresses springs 15 and 17.

Each arm of casing 1, 2 is embraced by a steel collar 19 (Figs. 1 and 3) the ends of which are bolted to the corresponding arm 20 of a four-armed steel member formed of two steel bars

crossing each other, one of the latter being formed integral by stamping with an axial shaft 21 (Fig. 10). A steel plate is inserted between the ends of collar 19 and the bolt heads or nuts to ensure better repartition of the wrenching force. Bars 20 may be assembled by any means, for instance by one of them being forced through a transverse notch of the other one. The lower end of shaft 21 is provided with a strainer 21a (Fig. 3). Bars 20 and shaft 21 are bored axially in such a manner that oil introduced into shaft 21 may flow into the casing via strainer 21a, canal 8 and passages 9.

Shaft 21 is rotatable within a vertical steel column 22 (Fig. 1) which is bolted to an internal spar 23 of an aircraft wing, the spar 23 being diagrammatically illustrated in Fig. 1 with its upper and lower parts in section. Rollers are interposed between shaft 21 and column 22. The upper end of shaft 21 is provided with a bevel gear 24 which is keyed thereon by means of a vertical keyway 24a (Fig. 13), the said gear resting on a roller bearing 25 itself supported by a plate 26. And above gear 24 shaft 21 has a circular recess engaged by a ring 27 (Fig. 13) formed of two halves screwed with each other. Shaft 21 is thus prevented from sliding down.

Gear 24 meshes with a pinion 28 carried at the end of a horizontal shaft 29 driven by the engine through an appropriate speed reducing set. It is of advantage to dispose for shaft 29 of two speeds corresponding to substantially 600 and 750 R. P. M. for shaft 21. A cross member 25a is disposed between the end bearing of shaft 29 and the upper part of spar 23 to distribute evenly the lifting forces.

On each shaft or tail 3, externally of casing 1, 2, there is secured a layer 30 (Fig. 8) of anti-friction alloy formed of two semi-cylindrical sheets fixed by means of appropriate screws. A sleeve is loosely mounted on this layer, such sleeve being made in two parts of light alloy with an inner steel sheet (which may be in two parts) wound around layer 30 to form a frictional lining in contact therewith and with two lateral pairs of protective steel sheets 31 and 32 (Fig. 8) extending close to shaft 3. On this sleeve there is secured an arcuate base 33 integral with a rod 34 (Figs. 8 and 16) extending radially of shaft 3, but having its end bent longitudinally of said shaft to carry a roller 35. Base 33 is fixed by means of screws, as shown and moreover two steel collars 36 embrace the said base together with its supporting sleeve; the ends of such collars 36 being bolted together with the ends of the inner steel sheet. The lateral sheets 31 and 32 are also assembled by screws and by small steel tongues 37. The two halves of the sleeve are formed with opposed protruding lugs 38, 39.

It will be understood that the unit thus formed may oscillate smoothly on shaft 3 under the action of roller 35, as hereinafter explained. Axial displacement on shaft 3 is prevented by means of two end rings 40 (Fig. 3) fixed on shaft 3.

On the outer end of each arm of casing 1, 2 there is laterally fixed a block 41 having a projecting cog 41a engaging a groove formed in the casing arm (Fig. 9). Block 41 is secured by means of a steel collar 42 which is moreover fixed to the casing by means of screws such as 43. Collar 42 has its ends bolted to block 41 by bolts 44. Block 41 may be made of light alloy; it carries two horizontal steel rods 45 extending one above the other on one side of

the said block, the said rods forming shafts for elongated rollers 46 rotatably carrying a sleeve 47 (Figs. 7, 8, 9 and 16) having opposed protruding lugs 48 connected through parallel connecting rods 49 with the aforesaid lugs 38, 39 corresponding to the next arm of casing 1, 2, as clearly shown in Figs. 3, 8 and 16. On the free end of rods 45 (Fig. 9) there is fixed a washer 50 to retain oil or grease and to prevent rollers 46 from moving longitudinally under the action of centrifugal force. Sleeve 47 is moreover internally lined with thin steel sheets to prevent wear, since the said sleeve and rollers 46 are made of light alloy.

Referring to Fig. 8 it will be understood that when the unit 31, 32, 33, 34, 35 oscillates, sleeve 47 is oscillated in unison therewith.

Sleeve 47 has an anti-friction lining 51 (Fig. 6) which is fixed thereto by any appropriate means, for instance by means of screws, and it rotates within a steel collar 52 which is bolted to another steel collar 53 screwed upon casing 1, 2 (Fig. 6). This connection is re-inforced by rigid steel members 54 which are also clamped with the bolts 55. And sleeve 47 is provided with rings 56 (Fig. 3) each side of collar 52 to prevent lateral sliding.

Sleeve 47 carries a cogged steel sector 56a (Figs. 7 and 16) screwed thereon which meshes with another steel sector 57 clamped on shaft 3. Sector 57 being smaller in radius than sector 56, it will be understood that for a limited angle of oscillation of roller 35 about shaft 3, the said shaft 3 itself is oscillated through a much larger angle. In the embodiment illustrated, the angle of oscillation provided for roller 35 is of 24° 49' and it corresponds to an angle of oscillation of 90° for shaft 3 and consequently for blade 10. The radial portion of rod 34 is 101.5 millimeters long and at the uppermost position of roller 35 the axis of the latter is 98 millimeters above the axis of tail 3, this distance being 78 millimeters when roller 35 is at the lowermost position.

Sector 56a screwed to sleeve 47 is moreover secured through an intermediate member 58 of light alloy provided with ribs 58a which fit into notches provided in sleeve 47, the said member being in turn fastened to sector 56a by means of small steel tongues 59. Sleeve 47 is thus rotatably retained by rollers 46, connecting rods 49, collar 52 and the reaction of the intermeshing cogs of sectors 56a and 57.

At the lower end of column 22 (Figs. 1, 2 and 12) there is a pair of opposed pins 60 forming pivots for a pair of lugs 61 secured to a plate 62 made of pressed aluminum alloy. Plate 62 is also provided with an angle member 63 carrying a pivot 64 for a vertical controlling rod 65 (Figs. 1 and 2) attached to a bell-crank lever 66 pivotally mounted within the wing spar 23, the said lever 66 being in turn actuated by means of a horizontal tube 67 adapted to be controlled from the cockpit of the craft through any appropriate gearing. It will be understood that plate 62 may thus be tilted about pivot pins 60. As indicated in Fig. 2, plate 62 has a central hole of appropriate diameter to accommodate the lower end of shaft 21, and it is to be understood that the tilting motion which may be imparted to the said plate is limited.

Plate 62 carried along its periphery a U-shaped channel member 68 (Figs. 1, 3 and 11) adapted to form a guide for rollers 35 during the rotation of shaft 21 together with the associated parts forming the rotor proper. As indicated in Fig. 11

rollers 35 have a slightly rounded periphery due to which they fit within member 68 with limited play in spite of the inclination of the guide 68. The latter is secured to the rim of plate 62 by means of square members such as illustrated at 69 in Fig. 14 and 70 in Fig. 15. Member 69 has two pairs of horizontal lugs, the upper one being adapted to fit on the rim of plate 62 while the lower one embraces the channel member 68, as indicated at the left part of Fig. 1. Since, as described below, the height of member 68 with respect to the blades varies along the periphery of plate 62, the lower pair of lugs (Fig. 14) are of course oblique along the slopes of member 68, and at the uppermost position of member 68 they are shown in Fig. 1 (right) and in Fig. 15.

Considering now Fig. 2 wherein arrow 71 indicates the direction of rotation of the rotor and arrow 72 the normal direction of flight of the aircraft (which is at about 8° with respect to the axis of pins 60), the channel or guide member 68 rises from A to B, then sinks from B to C and remains low and horizontal from C to A, the angle of slope being very small, say of 1° 30' owing to the suggested diameter of plate 62 (960 millimeters externally).

It will easily be grasped that when plate 62 is somewhat tilted from its horizontal position the angle of oscillation of the blades from their horizontal position may be varied at will.

The operation of my improved device is as follows:

It will be supposed that the aircraft is provided with a rotor under each wing as clearly shown in Fig. 21. Plate 62 being horizontal, the U-shaped guide-way 68 is secured under it at the position shown in full lines in Figs. 1 and 17, that is the 180° horizontal portion of the said guide-way is on one side of the line AC of Fig. 2 and the 180° slant portion thereof is on the other side. The device illustrated has the horizontal portion of the guide-way on the left side and the symmetrical device under the other wing of the craft must have this same portion on the right side.

When shaft 29 inside the wing is clutched with the engine, the rotor is caused to rotate and rollers 35 follow the U-shaped guide-way 68. When they are running on the horizontal portion thereof, the blade pitch is set at 0°. When a roller reaches point A (Figs. 2, 17 and 18) it begins climbing up and in acting so it rotates about the corresponding blade axis. When a roller has reached point B, the angle of its supporting rod 34 (Fig. 8) with a horizontal plane is then 75° in the construction illustrated. A larger angle would impair the smooth running of the rollers and would introduce risks of blade pitch inversion. It will be remarked that the rollers are pulled and not pushed.

The roller supporting rods 34 being secured by means of screws and collars (Figs. 3 and 8) to sleeves 31, 32 the latter which are loose on the blade tails will impart to connecting rods 49 fastened to lugs 38, 39 a to and fro movement. Since these connecting rods are connected with lugs 48 of sleeves 47 (Figs. 3, 8 and 16) the latter will be oscillated in unison with sleeves 31, 32 and through the same angle (24° 49' in the construction illustrated). The cogged sectors 56a (Figs. 7 and 16) secured to sleeves 47 will transmit this oscillating movement to the small sectors 57 with which they are in mesh. The ratio between the radii of sectors 56a and 57 being 3.626 to 1, the latter will oscillate through an

angle of 90° (24° 49' multiplied by 3.626). And since sectors 57 are secured to the blade tails, the blades will also oscillate through 90° about their own axes. The inertia torques or forces of the blades, sectors and other reciprocating parts will be damped by the coil springs 15 and 17 (Figs. 6 and 16), whereby the strains imparted to the guide-way 68 will be suppressed or reduced. This explains the necessity of small angles of incidence for the slopes of the guide-way (in the present case 1° 30').

When rollers 35 run upwardly from A to B (Figs. 2, 17 and 18) the blade pitch increases from 0° at A' to 90° at B', and when they run downwardly from B to C, the blade pitch decreases from 90° at B' to 0° at C'. The line AC (Fig. 2) which joins the ends of the horizontal portion of guide-way 68 is at the same time the projection on a horizontal plane of the oscillation axis of plate 62 (line joining the pivoting pins 60); the line A'C' is the line of flight. Figs. 17 and 18 clearly show the slopes of the guide-way and the variations of the blade pitch resulting therefrom.

It will be understood that such an operation results in a propelling force imparted to the craft, the steering of which is ensured as usual through fins and tail rudder.

When hovering is wanted, the pilot pulls tube 67 (Fig. 1) whereby bar 65 is raised by the crank-bell lever 66. Plate 62 is thus caused to oscillate about pins 60 (axis AC of Fig. 2) through such an angle that point D is raised through 10 millimeters and point B lowered through also 10 millimeters. The guide-way 68 then assumes the position shown in dash lines in Fig. 17 and the curves representing the inclinations of the various parts thereof and the variations of the blade pitch are those indicated in Fig. 19. It will be seen that the blade pitch increases from 0° to 36° along arc A'B', then decreases from 36° to 0° along arc B'C', increases again from 0° to 36° along C'D' and again decreases from 36° to 0° along D'A'. There is no more horizontal resulting force applied to the craft but only a vertical lifting component, as in a helicopter. In the construction illustrated the slope of the two portions of guide-way 68 is then 1° 7'.

Owing to the vertical radius between pins 60 and the different parts of guide-way 68, the oscillation of plate 62 causes a slight vertical displacement of points A and C. But this displacement is negligible; in the construction illustrated, supposing that the distance above-mentioned is 116 millimeters, the vertical displacement of points A and C is .038 millimeter and the residual blade pitch resulting therefrom would be less than 0° 7'.

Lateral stability of the craft could be ensured by declutching a rotor during a short instant, or in the case of several engines by adjusting the throttle valves thereof. Longitudinal stability may be ensured by means of an additional variable pitch two-bladed air-screw with vertical axis disposed above or beneath the aircraft tail; this additional air-screw would be stopped with blades disposed along the fuselage during forward flight.

For flying backwards plate 62 is tilted a little more than for hovering, point D being raised through about 15 millimeters above the position of normal flight. Guide-way 68 then assumes the position illustrated in dotted lines in Fig. 17 and the curves representing the slopes thereof and the variations of the blade pitch are those

of Fig. 20. It will be seen that the blade pitch varies from 0° to 16° along A'B', from 16° to 0° along B'C', from 0° to 58° along C'D' and from 58° to 0° along D'A'. Owing to the difference between the incidences at D' and B' the horizontal reactions are no more balanced and there is a propelling component which tends to move the craft backwards. The utmost slope of the guide-way is then 1° 50'; the variation in height of points A and C is about 1 millimeter and the residual blade pitch resulting therefrom is less than 0° 19', which is quite negligible.

In order to turn the craft when hovering, whatever may be the number of rotors, it would be sufficient to set one of them under a wing for forward flight and another one under the other wing for backward flight; with the same pitch on both sides the aircraft would turn without banking. For instance under one wing a plate 62 could be set with its point D raised through 15 millimeters while under the other wing a plate 62 would be set with its point D raised through 5 millimeters.

With a 160 H. P. engine a pair of four-bladed rotors of the kind illustrated rotating at 750 R. P. M. and provided with blades of 800 x 500 millimeters will develop while hovering a lift of about 2650 lbs. which would enable an airplane weighing 2000 lbs. to hover up to about 9,000 feet and a four-rotor airplane weighing about 3,500 lbs. to hover up to about 12,000 feet with a 320 H. P. engine. Longer blades would provide still better results. Of course other combinations of speeds and dimensions of blades would be of advantage. For instance with 400 to 500 R. P. M. instead of 600 to 750 and blades of 1200 x 500 millimeters, the same results as above could be obtained.

With blades weighing 32 lbs. 4 oz. having their center of gravity at 60 millimeters from the blade axis and rotating at 750 R. P. M. the springs may have 1.5 coils of steel wire of 3.5 millimeters in diameter to provide an external coil diameter of 20 millimeters. The inertia torques are reduced when hovering, since the maximum angular stroke of the blades is then of 36° instead of 90° within the same time. Moreover the springs prevent the rollers from going sharply up and down in their guiding channel owing to the small vertical play which should be provided to permit their free rotation.

It should be pointed out that landing and taking off may occur either as a helicopter or as an airplane, since the use of warping ailerons and slotted flaps is not hindered.

For flying over sandy countries the rotor may be protected by an appropriate cowling as explained below in the case of marine craft.

While I have described my improved rotor as applied to an aircraft, it must be understood that it may also be applied to ships. In such a case a pair of rotors would be fixed each side of the longitudinal axis of the ship at the rear thereof. The horizontal driving shafts would be either longitudinal to the ship or oblique according to the shape of the hull and they would be connected with the engine shaft or shafts through the hull. Each rotor would be enclosed within an appropriate protective casing formed of two parts. The upper one would be formed by a sheet screwed upon the vertical periphery of the fixed plate 62 and extending down to the blades. The lower part would be in the form of a trough screwed under the rotor casing and rotating therewith; it would extend up to the

blades. The space between these two parts would be closed by means of flexible slips screwed to the fixed upper part and raised by the blades during their rotation. The slopes of the guide member would extend over half a quadrant in such a manner that the blades would remain vertical during a full quadrant. The bevel gearing driving the rotor would be protected within a cowling and the plate carrying the guide member (plate 62) would be fixedly secured to the hull. Of course all parts would be made of steel.

I claim:

1. A multi-bladed rotor device for the purpose set forth comprising a casing adapted for rotation about a substantially vertical axis; blades radially disposed around said casing, each of said blades being formed with a radial tail oscillatably supported by said casing, each of said tails comprising a portion exterior to said casing; a non-rotatable circular guide member disposed at a variable height co-axially to said casing; a plurality of sleeves, each loosely carried by one of said tails on the portion thereof exterior to said casing; a plurality of arms, each radially secured to one of said sleeves; rollers at the ends of said arms, said rollers being guided vertically by said guide member to be vertically reciprocated in unison with rotation of said casing; a plurality of oscillatable members carried by said casing, each at a distance from one of said sleeves and the axes of oscillation of said oscillatable member and of said sleeve being parallel; a pair of substantially opposed connecting rods to connect each of said sleeves with the corresponding oscillatable member; a cogged sector secured to each of said members; and another cogged sector secured to each of said tails to mesh with said first-named cogged sector, said last-named cogged sector being smaller in radius than said first-named cogged sector.

2. In a multi-bladed rotor device as claimed in claim 1, said non-rotatable guide member being U-shaped in section, with the U opening towards the axis of said casing and each of said rollers having its axis of rotation substantially always parallel to the axis of the corresponding blade.

3. In a multi-bladed rotor as claimed in claim 1, said non-rotatable circular guide member forming a rigid unit tiltable about a transverse axis substantially intersecting the axis of rotation of said casing.

4. A multi-bladed rotor device for craft propulsion comprising in combination a hollow substantially vertical column secured to the craft; a vertical shaft rotatably carried by said column; a casing at the lower end of said shaft below said column, said casing being formed with a plurality of hollow radial arms; rotatable radial shafts each radially supported by one of said arms, each of said shafts extending outwardly of said casing first in the form of a cylindrical tail and thereafter in the form of a blade; a non-rotatable substantially rigid circular plate carried by the lower end of said column co-axial to the same and above said casing; a U-shaped circular guide member also co-axial to said column and secured under said plate with the U-opening inwardly; a plurality of sleeves each loosely carried on the portion of one of said radial shafts exterior to said casing; a plurality of arms each radially secured to each of said sleeves; a plurality of rollers each rotatably secured at the free end of each of said last-named radial arms with the roller axis parallel to the axis of the correspond-

ing radial shaft, said rollers engaging said U-shaped circular guide-member to be vertically reciprocated thereby; a plurality of oscillatable members carried by said casing each at a distance from one of said sleeves and in parallel relation thereto; a pair of connecting rods to connect each of said oscillatable members with the corresponding one of said sleeves; a plurality of cogged sectors each secured to one of said radial shafts on the portion thereof exterior to said casing; and a plurality of cogged sectors each secured to each of said oscillatable members, said last-named cogged sectors being larger in radius than said first-named cogged sectors and each of said last-named sectors meshing with one of said first-named sectors.
